FLANGE CURLING MACHINE

William F. Butler, Hillside, N. J., assignor to
American Can Company, New York, N. Y., a
corporation of New Jersey

Application June 23, 1933, Serial No. 677,323

16 Claims. (Cl. 153—59)

The present invention relates to bending or curling apparatus and has particular reference to apparatus for curling the flanges of can ends and the like by supporting the end walls adjacent the flanges throughout the flanging operation so that all shapes of ends, oblong as well as round or oval are evenly curled with speed and precision.

In curling the flanges of oblong can ends such as those having straight sides joined by rounded corners the section of the right angle wall of the usual countersink adjacent the flange along the straight sides is more flexible than the wall adjacent the rounded corners and this fact influences the curling of the edges when unsupported, as is the usual practice, and there is likely to develop considerable unevenness in the curl of the flange particularly in the noncircular end and any unevenness affects the subsequent seaming of the ends on to can bodies.

The present invention is concerned with producing a more uniform and regular curl on the flanges of can ends regardless of shape and size and contemplates movement of flanging rollers in a path of travel around a stationary chuck by which the can ends are individually held with the counter-sunk walls adjacent the flanges of the ends fully supported during the entire curling operation.

An important object of the present invention is the provision of a flange curling machine having a continuous action wherein the can ends are received in succession and are individually and automatically subjected to the curling operation while they are fully supported on a stationary chuck.

The invention also contemplates the addition of a turnover device, as a part of such a flange curling apparatus, which reverses the position of the ends so that they may be received direct from a forming or drawing press in which it is most convenient to draw the central panel of the ends up. This turnover device, receiving the ends in this drawing position, turns them over with the sunken panel turned down, which is the proper position for raising into a curling head located above the line of travel of the ends. The ends are lifted into chucked position on a stationary chuck located in the curling head.

The invention furthermore contemplates what in some cases is highly desirable, namely, the additive feature of an automatic stacking device for placing the fully curled ends into a holding magazine.

An important object of the invention is the provision of a flange curling machine of the char-

acter described which carries the can ends in processional order through the machine's operating stations while keeping them substantially visible along one side and easily accessible, thereby permitting inspection of the ends throughout the various operations of the machine.

Yet another desirable feature of the present invention is the provision of a hinged curling head which may be swung back and away from the can ends in and adjacent to the curling station, permitting full inspection or removal of the ends without disconnecting or disturbing the actuating mechanism. The machine cannot be operated, however, as long as the hinged head is not in proper position, but when in curling position the head is firmly held in place for the curling operation.

Numerous other objects and advantages of the invention will be apparent as it is better understood from the following description, which, taken in connection with the accompanying drawings, discloses a preferred embodiment thereof.

Referring to the drawings:

Figure 1 is a front elevation of an apparatus embodying the present invention;

Fig. 2 is a part sectional, part plan view of the machine on an enlarged scale, illustrating the path of travel of can ends therethrough;

Fig. 3 is a longitudinal sectional view taken substantially along the line 3—3 in Fig. 2;

Fig. 4 is an enlarged transverse sectional view taken substantially along the line 4—4 in Fig. 1, parts of the seaming head being shown in full;

Fig. 5 is a transverse sectional view taken substantially along the line 5—5 in Fig. 2 and looking toward the feed or entrance end of the apparatus;

Fig. 6 is a sectional detail taken substantially along the line 6—6 in Fig. 5;

General mechanical features

10 In the apparatus disclosed in the drawings as a preferred embodiment of the present invention, oblong can ends 21 (Figs. 2 and 3) are received in the upper end of an inclined chute 22 located at one end of the apparatus. This chute is preferably mounted upon a bracket extension 23 (see also Fig. 1) of a main frame 24. An intermittently movable turnover wheel 25 is carried on a horizontal shaft 26 journaled in bearings 27 15 formed in the frame bracket 23 and this turnover wheel is directly below the discharge or lower end of the chute 22.

20 The can ends 21 move by gravity down the chute 22 and the line of ends are held in the chute by yielding devices 28 which engage the lowermost end at a station A (Fig. 3). These ends are all faced the same way as they rest in 25 processional order in the chute and where these ends are coming direct from a drawing and end forming press their central panel sections are faced upwardly as shown. When in such position they will be turned over before being brought into curling position and it is for such a purpose 30 that the turnover wheel 25 is used. Were the ends in the chute 22 faced in the opposite direction the turnover wheel would not be used and would be removed from the can travel.

35 The turnover wheel 25 is formed of a pair of spaced discs 31, the inner face of each disc being cut across with grooves 32. Each groove extends from the periphery of the disc generally toward the center but offset a slight distance. The outer or peripheral end of each groove flares outwardly at 33, these groove ends in each disc being equally spaced around its periphery. A pair of flared groove mouths 33, one on each disc, are brought into register (at a station B) with the lower discharge end of the chute 22 at each rest period of the turnover wheel.

40 50 The discs 31 are intermittently or step moved as their supporting shaft 26 is partly rotated and at each movement a new pair of grooves 32 is presented to the discharge end of the chute (station B). Feeding devices 35 operate when the discs 31 are at rest to move the lowermost can end 21 from its held position within the yielding devices 28 (station A) and to insert it into the aligned grooves at station B.

55 60 The top part of the frame 24 is formed as a horizontal table 36 and it is along this table that the can ends are moved into and out of the curling head, after they have been turned over by the discs 31. In this turn over operation the can end 65 70 75 21 is fed into the discs 31 at station B, is carried up and over in two succeeding step movements of the discs through two idle stations C and D and at the third step movement is brought into its third position of rest at a station marked E in Fig. 3.

This end is now in a horizontal position and is in substantial alignment with the top of the table 36. In the three step movements just described the can end has been turned over from the

inclined position with its panel face up into horizontal position with its panel face down.

Transfer devices 41 operate in a horizontal plane and along the table 36 to remove the turned-over end from the discs 31, moving it first 5 from station E into an idle station F (Figs. 2 and 3) and thence into a curling station G. At G the end is in alignment with a lift device 42 (Fig. 4) located beneath a curling head 43.

The can end 21 at the curling station G is raised 10 by the lift device 42 and is clamped onto a stationary chuck 44 (Figs. 3 and 12) carried in the curling head 43. This chuck is formed with a lower face that is contoured to closely fit the central panel of the end 21 as is usual in all chuck 15 constructions and this chucking of the end backs up its flange equally at all surrounding peripheral positions and reinforces the parts of the flange for the curling operation.

20 While in raised position and while so clamped between the parts 42, 44, the flange of the end is engaged by curling rollers 45 carried on oscillating levers 46 mounted in the curling head. These rollers curl the peripheral edge of the flange as they are carried around the stationary chuck. 25 The curling rollers follow the flange periphery and gradually move closer in as the curling proceeds, the swing of the levers 46 determining this action.

30 After curling, the end is lowered and again deposited on the table 36. It is then further advanced by the transfer devices 41, first through an idle station H (Figs. 2 and 3) and thence over a lifting plunger 48 at a stacking station J. Plunger 48 raises the curled end from the table 35 and inserts it into the lower end of a stack of ends within a storage magazine 49. In the foregoing only a brief description of the mechanical parts and operations has been attempted. These 40 will now be described in detail.

Can end receiving chute and end delivery

45 The feeding chute 22 (Figs. 2 and 3) is preferably formed by a pair of spaced blocks 55 each of which is secured by bolts 56 to the bracket 23. These blocks are separated a distance slightly in excess of the drawn central panel (designated by the letter 57) of the end 21. The panel of each end is surrounded by the outwardly extending flange (marked 58) which is to be curled.

50 55 A grooved guide rail 59 is mounted on each block 55 adjacent its inner edge and the can ends in the present embodiment come into the chute with the drawn panel 57 up, this being the position as received from a drawing press or the like. Opposite sides of the flange 58 of the ends pass into and move along the grooves of the guide rails 59. The can ends move by gravity down the inclined chute. It is the lowermost can end of the line of ends in the chute that is engaged by the yielding devices 28, as previously described.

60 65 These yielding devices comprise fingers 61 which are pivoted at 62 on the upper surfaces of the blocks 55. The lower end of each finger 61 is held in the path of travel of the can ends by a leaf spring 63 which is secured to a projection 64 extending outwardly from the surface of the block and which engages the finger near its pivot 62. The upper end of each finger 61 when holding a can end rests against the end of an adjusting screw 65 which is threaded in the projection 64 and which may be adjusted to position the lower end of its associated finger. A small block 66 is secured upon the upper face of each block 55 and 70 75 75

provides a guide for the can end as it moves from the chute.

The feeding device 35 for moving the lowermost can end from the chute and for placing it into the turnover wheel 25 is best shown in Fig. 3 and comprises a finger 71 which is pivoted on a pin 72 carried in a hollow block 73 which slides up and down on an inclined strap 74 secured at its upper end to the bracket 23 by a bolt 75 and at its lower end to the table 36 by a bolt 76.

Strap 74 is located beneath and centrally of the can end travel through the chute and its upper end extends to a point beyond or above the pivoted fingers 61. The lower end of the strap is formed with a collar section 77 (Figs. 2 and 3) which encircles the shaft 26 intermediate the discs 31.

Movement of the block 73 to raised position arranges its finger 71 back of the lowermost cover 21. A leaf spring 78 carried in the block and resting under the finger yieldingly moves it into position for engagement with the lower vertical wall of the end panel 57 at such a time.

The block 73 and the finger 71 are moved downwardly to effect the removal of the engaged can end 21 from the chute. In this movement the end is forced between and past the lower ends of the fingers 61 which move back against the action of their springs 63 and permit the end to pass between the blocks 66 and into a pair of presented grooves 32 of the turnover discs 31.

Block 73 is pivotally connected at 81 to the upper end of a bent connecting strap 82 (Figs. 3 and 5) which is pivoted at 83 to an outer arm 84 of a compound crank arm 85 formed on one end of a horizontal shaft 86. The shaft 86 is journaled in bearings 87 formed in the frame 24 and supports a spur gear 88 which meshes with a similar gear 89 (see also Fig. 4) which is keyed to a horizontal shaft 91.

The shaft 91 is journaled in bearings 92 formed in the frame 24 and is rotated through the medium of a worm gear 93 keyed on one end of the shaft 91. The worm gear 93 meshes with a worm 94 (Figs. 2 and 4) which is secured centrally of a shaft 95 journaled in bearings 96 formed in the frame 24 and extending upwardly from the table section 36.

The driving power for the machine is furnished by an electric motor 97 mounted upon a bracket 98 secured to the frame 24. A motor shaft 99 of the motor 97 carries a gear 100 which meshes with a gear 101 secured to one end of the shaft 95. In this manner the motor shaft rotation is transmitted to the shaft 86 which in turn carries the crank arm 85 around and this actuates the block 73 and its finger 71 for a feeding stroke.

Turnover wheel and can end turnover

The intermittent actuation of the turnover wheel 25 is effected by means of parts which impart step rotation to the shaft 26 in the following manner. The shaft 26 carries a sprocket 105 (Figs. 2, 5 and 6) over which a chain 106 operates. This chain also passes over a sprocket 107 which rotates on a Geneva wheel stationary shaft 108 fixed in a bearing 109 formed in the frame 24.

The sprocket 107 is secured to or is an integral part of a Geneva wheel 115 which is intermittently rotated on the shaft 108 by a roller 116 engaging in radial slots 117 formed in the Geneva wheel. The roller 116 is mounted on a pin 118 extending outwardly from one face of the gear 88. The hub of the gear 88, designated by the numeral 119, is cut away at 121 to permit move-

ment of the Geneva wheel 115 by engagement of the roller 116 within each slot 117.

The uncut part of this hub 119 provides for the locking of the Geneva wheel on its rest period by rotating within pockets 122 formed in the wheel, this being a usual Geneva unit construction. By the described connections, the continual rotation of the shaft 86 is imparted as an intermittent movement to the shaft 26 and the latter advances the turnover discs 31 in a step by step movement.

Can end transfer from station to station

Transfer of the can end from the turnover wheel 25 into the curling station by the transfer devices 41 now follows. A feed bar 125 (Figs. 3 and 8) is provided as part of such devices. This feed bar moves back and forth in a longitudinal slot 126 formed in the table 36, the bar in cross section presenting the form of an inverted T. The feed bar 125 is held against upward displacement by plates 127 located in slots 128 cut in the upper surface of the table 36.

As the turnover wheel brings the can end 21 into its horizontal position at station E, the feed bar is in its rear position (Fig. 3). A fixed finger 131 is formed on the rear end of the feed bar and projects upwardly above the surface of the table. This finger 131 is behind the can end as it comes to rest in station E.

While the turnover wheel remains stationary on its period of rest (Figs. 2 and 3) the feed bar moves forward and the finger 131, engaging the can end, slides it out of its grooves 32 and over the surface of the table 36 as it transfers the end 35 into the idle station F.

To effect this feeding movement the feed bar 125 at its rear end has rack teeth 132 cut in its lower face. These teeth are engaged by a segmental rack 133 formed on the upper end of an arm 134 which is secured to a rock shaft 135 (Figs. 3 and 5). Shaft 135 is mounted in a boss 136 formed in the frame 24. The arm 134 is cut out in its central section to provide a rectangular opening 137.

The compound crank 85 extends through the opening 137, the rear part being connected by a cylindrical section 138 with the outer arm 84. A pair of split blocks 139 encircle and provide a bearing for the cylindrical part 138 and these 50 have sliding movement within the opening 137 of the arm 134. As the double crank moves with the rotation of its shaft 86, the cylindrical part 138 of the arm is carried in a circular short crank path, the pivot 83 of the strap 82 describing the 55 full or long crank movement. It is these two movements that constitute the double crank action.

At the same time the blocks 139 slide up and down within the opening 137 and transmit 60 a rocking motion to the arm 134 with its rock shaft 135. The resulting rocking movement of the segmental rack 133 through the rack section 132 of the feed bar moves the latter back and forth within its table slot 126.

The can end 21 coming into station F passes over and depresses a pair of hold back fingers 145 (Figs. 2 and 10). Each finger is pivotally mounted at 146 in a block 147 positioned on the table 36 at one side of the feed bar 125. A leaf spring 148 carried in the block 147 engages beneath the forward end of the finger and yieldingly holds it in raised position.

As the can end 21 strikes against and passes over the fingers the springs 148 yield and the 75

forward ends of the fingers are thus depressed. The can end comes to rest with its drawn panel section 57 just in front of the fingers and when the feed bar 125 returns on its rear stroke the fingers prevent a corresponding return movement of the end.

During the next forward movement of the feed bar 125 when the end 21 is further advanced into the curling station G a spring held feed finger 10 149 (Figs. 2 and 3) pivoted on the feed bar, is used. This finger is held in its raised end feeding position by a leaf spring 150. As the feed bar moves back, following the transfer of the end into station F and while the end is being held by the 15 hold back fingers 145, the finger 149 is depressed as it passes beneath the end panel and thus comes into feeding position behind the end at station F.

During the passage of can ends 21 across the 20 table 36 from station E through the intermediate stations and into the stacking station J the opposite sides of their flanges 58 ride over a pair of spaced guide or support bars 151, 152 (Figs. 8 and 9). These bars rest upon and are carried by the table 36 and are formed along their inner 25 edges with upwardly projecting ribs 153, 154 along which the end flanges ride.

The can ends during their travel along the bars 151, 152 are prevented from upward displacement by other guide or retaining bars 155, 156 30 which are mounted upon the bars 151, 152. Bars 155, 156 are formed along and under their inner edges with longitudinally extending grooves 157, 158 through which the end flanges pass.

The bar 155 is slotted at 161 (Figs. 2 and 9) 35 and shouldered bolts 162 pass through the slots and are threadedly seated in the bars 151. These bolts 162 prevent upward displacement of the bar 155 but have clearance within the slots 161 allowing for movement of the bar toward and 40 away from the track of the can ends.

The bar 155 is normally held inwardly by 45 spring pressed pins applied to its ends. As illustrated in Figs. 2 and 9, the bar 155 is extended at its ends in projections 165 which are disposed just inside of blocks 166 bolted at 167 to the bar 151. Each block 166 carries a pair of pins 168 which project from the inner face of the block and these pins are backed up by springs 169 enclosed within openings formed in the block. 50 A screw plug 171 threadedly engages in the block and holds the spring confined within its opening. A detail of one of the pins 168 with its associated spring 169 is shown in the lower left hand corner of Fig. 9.

55 Provision is made for swinging back the bar 155 against the holding action of the springs 168 so that access may be had to can ends. For this purpose a pair of shift members 174 (Figs. 2, 8 and 9) are provided, each being formed with a 60 stepped cylindrical shank 175 which is mounted for partial rotation within a counter-sink seat 176 formed in the bar 151. This cylindrical shank carries an upwardly extending head 177 which is eccentrically mounted relative to the 65 vertical axis of the shank and which extends loosely through a slot 178 cut through the bar 155.

A finger pin 179 is inserted in one side of the upper part of the head 177 and manual shifting 70 of the pin rotates the shank 175 within its seat 176. This moves the head 177 in the slot 178 and pulls back the bar 155 forcing back the pins 168. By swinging the two finger pins 179 simultaneously the bar 155 is moved from the

75 position shown in Fig. 2 to that illustrated in Fig. 9.

The bar 156 is also pin held in its end guiding and retaining position. Shouldered bolts 181 (Figs. 2, 8 and 9) are used to yieldingly and frictionally hold the bar 156 on the guide bar 152. The bolts 181 may be of the same construction as the bolts 162 of the bar 155. They extend through slots 182 cut through the bar 156 and prevent upward displacement of the bar while permitting a certain amount of lateral movement. A spring 183 (Fig. 8) surrounds the large part of each bolt 181 being confined between the bolt head and a washer 184 which is pressed down against the upper surface of the bar 156, thus providing a friction between the movable and stationary bars 156, 152. This same construction is equally applicable to the bolts 162 previously described.

The bar 156, like the bar 155, is formed with 20 end projections 185 (Figs. 2 and 9) which extend adjacent blocks 186 held on the bar 152 by bolts 187. A spring pressed pin 188 is carried in each block 186 and is yieldingly held with its end against the projection 185 in the same manner as the pins 168 are held against the ends 165 of the bar 155 as just described.

Can end lifting into curling head

At the curling station G, the can end 21 resting above and in axial alignment with the lift device 30 42 is raised into the curling head as previously described. This lift device comprises a cylindrical body 191 (Figs. 3, 4 and 12) which is disposed within a tubular sleeve 192 formed with a bottom flanged base 193 which rests upon the frame 24 35 and is secured by bolts 194. The upper end of this sleeve extends through an opening 195 cut through the table 36 and its upper edge is just beneath the table surface.

The sleeve 192 provides a slide bearing for the 40 cylindrical body 191 which is adapted to move upwardly when it carries the can cover into curling position within the curling head 43. The upper end of the body 191 is reduced into a head 196 which extends upwardly between the bars 45 151, 152 and when the body 191 and head 196 are in their lowered position, the latter is just beneath the can end 21 at the curling station.

The head 196 is also cut away at 197 to provide 50 a clearance passage for the transfer devices 41 and the top wall of this passage is cut through in a slot 198 to permit passage of a fixed feed finger 199 carried by the feed bar 125 and used for transferring the curled end from station G to station H as will be later described. This finger 55 is positioned just ahead of the lift device 42 as the cover 21 comes to rest above the lifter head 196.

The body 191 is raised and lowered by a cam device associated with the shaft 91 (Figs. 3 and 4). The sleeve 192 is cut away at 201 for clearance and the body 191 carries a pin 202 on which a cam roller 203 is rotatably mounted. The pin and roller project rearwardly into the 60 opening 201.

65 Roller 203 rests upon a cam section 204 of a double cam 205 carried on the forward end of the shaft 91 and the body 191 and parts carried thereby are supported by the cam. Rotation of the shaft 91 and the cam 204, operating through the roller 203, raises the body 191 and carries its head 196 upwardly against the cover and then lifts the latter into the curling head 43. In addition to the weight of the lift device the cam roller 70 75 75

203 is further held against the cam 204 by a spring device illustrated in Fig. 4.

The body 191 is formed in its lower end with a vertical bore 207 and a rod 208 extends upwardly into the bore, its lower end being anchored on the frame 24 within the base of the sleeve 192. A spring 209 surrounds the rod 208 and is enclosed in the bore 207. Its upper end engages a threaded washer 211 carried on the rod and its lower end engages a nut 212 threadedly secured in the bottom of the body 191 and closing off the bore 207, the nut 212 having free sliding movement on the rod.

Spring centering fingers 221, 222 (Figs. 12 and 15 13) disposed on opposite sides of the can end as it is raised by the head 196 press against the end during its lifting movement and center the end accurately for the curling head. These fingers have a slight back and forth movement in 20 slots 223, 224 cut in the under faces of the bars 155, 156.

Each finger is formed with an outer downwardly extending part 225 which carries a stop screw 226. This stop screw strikes against the 25 side wall of the bar 151, or 152 as the case may be, and limits the inward movement of a can end flange engaging inner edge 227.

Each finger 221 or 222 is formed with a second downwardly extending part 228 to which a bowed 30 leaf spring 229 is secured at its middle. Bars 151, 152 are formed with elongated pockets 231 which contain the parts 228 and springs 229 of the fingers. The two ends of each spring 229 rest upon the outer wall of its pocket 231 and flexure of 35 the spring yieldingly holds its associated finger in centering position.

Can end curling

At about the same time that the head 196 of 40 the lifting device engages the can end 21 at station G and before the end is released from the centering fingers, a knockout pad 241 (Figs. 3 and 4) of the curling head comes down into the can end panel 51 and clamps it firmly in position 45 on the head. This pad is preferably secured to or is an integral part of a rod 242 which extends vertically through the curling head. The curling elements, including the curling rollers 45 and their levers 46, are carried around rod 242.

50 The upper end of the rod 242 is adjustably secured to an offset section 243 of a slide 244 which is located in the upper part of the curling head 43. This slide has vertical movement within a slide-way 245 formed in the head and carries a rearwardly projecting pin 246 on which a cam roller 247 is mounted. This roller operates in a cam groove 248 formed in the periphery of a barrel cam 249 keyed on a sleeve extension 251 of a gear 252. The gear parts 251, 252 are rotatably supported on a shouldered stud 253 locked in a boss 254 formed in the curling head 43.

The gear 252 meshes with and receives rotation from a pinion 255 and this pinion together with a gear 256 turns as a unit with a sleeve 257 which is journaled in a tubular bearing 258 formed in the curling head 43. A worm gear 259 is keyed to the lower end of the sleeve 257 and the gears 255, 259 are locked together with the sleeve 257 by a bolt 261. The bolt 261 at its 70 lower or head end extends through a washer 262 seated in the worm gear 259 and its upper end is threadedly secured in the pinion 255.

Movement of the rod 242 is so timed that the knockout pad 241 is brought down into clamping 75 position on the can end as shown in Fig. 3 and

then as the end is lifted by the lift device 42, the pad 241 is correspondingly raised, maintaining its end holding action the while until it seats within the bottom of the chuck 44. The rod 242 at that time is at the top of its stroke and the can end is then clamped between the lift head 196 and the chuck 44 and is thus held in stationary position for the curling operation.

The gear 256 is bolted to and carries a gear 265 which has a slightly larger diameter and these two gears provide a differential drive through mating gears 266, 267 constituting a portion of the curling instrumentalities and actuating devices for moving the curling levers 46 around the stationary chuck 44.

The exact details of the curling head, it is believed, are not important for a full understanding of the present case, any suitable seaming head using the proper curling rollers 45 being sufficient. Such details will not be shown or described, the features already set forth providing the principal working parts of a proper apparatus. The mechanism for actuating the curling rollers 45 by means of the above described differential gear drive, Fig. 4, may be the same as disclosed in my prior Patent No. 1,972,866 dated September 11, 1934, on an application filed July 6, 1931 for a Double seaming head.

Hinging of curling head

The entire curling head 43 and parts contained within its housing may be hinged or swung around on the center of the shaft 95 (Figs. 2 and 4) without disconnecting it from its actuating mechanism. The curling head 43 is formed with spaced lugs 275 which are located at the ends of the worm 94, the shaft 95 passing through the lugs.

When the front of the curling head 43 is lifted, the teeth of the worm gear 259 merely slip around in the teeth of the worm 94 maintaining mesh at all times. The chuck 44, rollers 45, knockout pad 241 and other parts contained within the head are thus lifted clear of the can end 21 resting upon the head 196 of the lift device 42 at station G. This opens up the line of can ends on the table and with the removable bar 155 allows full visibility and accessibility.

Provision is made for holding the head firmly in curling position and to prevent inadvertent operation of the machine, if the head is not in such position, provision is also made to prevent operation of the driving motor 97 unless and until the head is so positioned. These two features will now be considered.

A bar 276 (Figs. 1 and 4) is carried within the head 43, its upper end being secured at 277 to the upper frame of the head and its lower end extending in front of the moving parts. This lower end is formed with a foot 278 which rests upon a bracket 279 bolted at 281 to the frame 24. A stop block 282 is bolted to the front and center of the bracket 279 and the lower end of the bar 276 rests inside of this block when the head is down.

A manually operated latch is provided for holding the bar 276 and locking the head in place. The foot 278 of the bar extends rearwardly (Fig. 4) and is adapted to be engaged by a head 283 of a short shaft 284, these constituting the latch referred to. Shaft 284 extends vertically through the bracket 279 and through a spacer block 285 resting upon the bracket. A manipulating handle 286 secured on the lower end of the shaft 284 permits latching and unlatching of the head.

Disengagement of the foot 278 unlocks the curling head 43 and it may then be swung back

into noncurling position as indicated by dotted lines in Fig. 4. A part of the rear wall of the casing for the head 43 is curved at 287 (Figs. 4 and 14) and this fits into and slides along a cylindrical wall 288 formed in the back of the frame 24. This forms a closed connection between the casings at all times. A stop ledge 289 on the head wall 287, striking against the top edge of the wall 288 limits the swinging movement of the head and holds the head in its raised position.

The device used to prevent operation of the motor 97 and by it the entire apparatus comprises an electric switch unit 291 (Figs. 1 and 14) which is interposed in the electric circuit which carries electric energy to the motor. The switch unit 291 has a fixed contact 292 and a movable contact 293. The latter is carried on an arm 294 pivoted at 295 in the switch housing.

The free end of the arm 294 carries a roller 296 which is lifted, with its arm 294, by a spring 297 when the roller is not depressed. At such times the circuit is broken in the switch and the contact points 292, 293 are separated. The curling head 43 is formed with a projecting ledge 298 on the side adjacent the switch and when the head is in proper curling position the roller 296 is engaged by the ledge and the arm 294 is depressed so that the contact points 292, 293 are brought together as shown in Fig. 14. The switch unit is then closed and current can flow through the motor 97.

Fig. 1 includes a diagram of a motor circuit wherein wires 299 pass between the contacts 292, 293 of the switch and the motor 97. It is necessary for the circuit including these wires to be closed in the switch unit 291 in order for electrical energy from any suitable source 300 to actuate the motor. When the head 43 is lifted into any position and is not in the lowered curling position the spring 297 holds open the contacts 292, 293 and the switch unit 291 is opened. The motor 97, and through it the machine, cannot then be operated and must remain inactive until correct positioning of the curling head closes the motor circuit.

Can end moved from curling head

After curling, the lift device head 196 moves downwardly and the knockout pad 241 moves with it, stripping the curled can end from the chuck 44 and again bringing it down in supported position on the bars 151, 152. At such time the fixed feed finger 199 on the feed bar 125 is back of the edge of the can end.

It reaches this position by moving back through the slot 198 of the head 196 and while the can end is raised and clamped in the curling head. It is because of this fact that finger 199 need not be spring pivoted as is finger 149. As soon as the end snaps in under the edges 227 of the fingers 221, 222 this feed finger 199 moves forward with the feed bar and transfers the end from station G into the next idle station H.

At station H the curled can end passes under a second pair of hold back fingers 301 (Figs. 2 and 11) which like the fingers 145 at station F extend upwardly in the path of travel of the can end and which are also depressed by the advancing end. The fingers 301 are identical in construction and function to the fingers 145 shown in detail in Fig. 10 and previously described. Fingers 301 prevent return of the end 21 with the return of the feed bar 125 which follows.

A spring pressed feed finger 302 carried on the feed bar 125 in advance of the fixed finger 199 moves under the end and comes to a feeding position back of the end when the feed bar returns for its next forward stroke. Finger 302 is pivotally mounted and spring held within the feed bar 125 and is of the same construction as finger 149 and functions in the same manner.

Can end stacking

On the next forward movement of the feed bar 125 finger 302 engages and transfers the can end from the idle station H into the stacking station J where it is in axial alignment with and directly beneath the magazine 49. From this position the end is lifted from the feed bar 125 and from the table 36 by the lifting plunger 48 and is inserted in stacked position into the bottom of the magazine 49, as previously described.

The lifting plunger 48 has sliding movement 20 within bearings 303, 304 formed in the frame 24 and is formed with a head 305 which picks up the can end when the plunger 48 is raised. Raising of the plunger is effected by the cam 205 on the shaft 91 (Figs. 3 and 4). The plunger 48 is formed with a toothed rack section 311 and a segmental rack 312 carried on one end of a lever 313 meshes with the teeth of the plunger.

Lever 313 is pivotally mounted on a pin 314 which is carried in lugs depending from the table 36. The opposite end of the lever 313 carries a cam roller 315 which rides upon the peripheral face of the double cam 205. Rocking movement of the lever 313 on its pin 314 raises and lowers the lifting plunger in proper time for insertion of the can end into the bottom of the magazine 49.

The plunger 48 adjacent its bottom end is formed with a vertically extending bore 316 (Fig. 3) in which a bolt 317 projects. This is the same type of holding device as for the body of the lift device 42 which included the bolt 208. The lower end of the bolt 317 is threaded engaged in the frame 24 and extends upwardly through a nut 318 threadedly secured in the lower end of the plunger 48 in which position it closes the bore 316.

A spring 319 surrounds the bolt 317 and its upper end engages the head of the bolt while its lower end rests upon the nut 318. This spring 50 pulling down on the lifting plunger holds the cam roller 316 against the cam 205.

The stack of ends 21 within the magazine 49 are retained in vertical position at two opposite corners between angle plates 325 (Figs. 2, 3 and 7). These plates extend upwardly from and are formed with horizontal feet 326 which are bolted at 327 on the table 36. The stack of ends 21 in the magazine are supported upon the upper ends of a pair of spaced dogs 331.

Each dog 331 is pivoted on a pin 332 carried in an insert block 333 which is located in a channel 334 formed in the foot 326. A spring 335 is held in each block insert and one end engages an extension 336 of the dog 331 and normally holds the upper end of the dog under the stack of ends. When the lifting plunger 48 is raised and the can end on the head 305 passes into the bottom of the magazine 49 the flange of the end snaps past the opposed dogs 331 and moves into position beneath the stack. The dogs 331, as soon as the end has passed, spring inwardly and back into supporting position under the action of their springs 335 and in this way the curled ends are stacked for convenient removal.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

10 1. I claim:

1. An apparatus for curling the flanges of can ends and the like, comprising in combination, a curling head, a stationary can end chuck in said head, curling instrumentalities in said head and 15 rotatable around said chuck for curling the flanges of said can ends, means for holding a said can end in said curling head and clamping it on said stationary chuck so that its flange is fully backed up and equally supported at all points around its 20 periphery, actuating means for moving said curling instrumentalities in and out during their rotation around said chuck for effecting said flange curling and reciprocable means for ejecting said can end from said head and said chuck after 25 the flange curling operation has been completed.

2. An apparatus for curling the flanges of can ends and the like, comprising in combination, a support for flanged can ends, a curling head located above said support, longitudinally reciprocable means for advancing can ends along said support into registry with said curling head, a stationary can end chuck in said head, curling instrumentalities also in said head and rotatable around said chuck for curling the flanges of said 35 can ends, means including said support to clamp a can end to be curled on said stationary chuck so that its flange is fully backed up and equally supported at all points around its periphery, and actuating means for positioning said curling instrumentalities relative to the flange of said held can ends and during their rotation around said stationary chuck for effecting said flange curling.

3. An apparatus for curling the flanges of can ends and the like, comprising in combination a horizontal table adapted to support flanged can ends, a curling head located above said table, said curling head including a stationary can end chuck, curling instrumentalities rotatable around said chuck for curling the flanges of said can 45 ends, transfer feeding devices reciprocable in said table for moving can ends therealong, means for lifting a said can end from said table and to clamp it on said stationary chuck, and actuating means for said curling instrumentalities for effecting the flange curling of said held can ends 50 during the rotation of said instrumentalities.

4. An apparatus for curling the flanges of can ends and the like, comprising in combination, feeding devices for successively engaging and conveying a plurality of can ends with one face of their flanges turned up, intermittently operable means cooperating with said feeding devices for inverting said ends to bring their opposite flange faces up, and curling instrumentalities for curling 55 said can end flanges while in their turned over position.

5. An apparatus for curling the flanges of can ends and the like, comprising in combination, feeding devices for conveying can ends with one face of their flanges turned up, means for turning over said ends to bring the said flange faces down, curling instrumentalities for curling said can end flanges while in turned over position, and means for arranging said curled ends in stacked 70 formation.

6. An apparatus for curling the flanges of can ends and the like, comprising in combination a chute for holding flanged can ends with one face turned up, an intermittently movable turnover wheel located at one end of said chute for turning over said ends to bring their opposite flanged faces up, feeding devices for moving a said can end into said turnover wheel when it is at rest, curling instrumentalities located adjacent said turnover wheel for curling said can end flanges, 10 and means for transferring said can ends from said turnover wheel into said instrumentalities.

7. An apparatus for curling the flanges of can ends and the like, comprising in combination, feeding devices for conveying can ends with one 15 face of their flanges turned up, means for turning over said ends to bring their opposite flange faces up, a table located adjacent said turnover means for supporting said turned over ends, a curling head located over said table and spaced 20 from said turnover means, transfer devices for moving said turned over ends into said curling head, and curling instrumentalities in said head for curling said can end flanges.

8. An apparatus for curling the flanges of can ends and the like, comprising in combination, a horizontal table adapted to support flanged can ends, means for bringing can ends to the receiving end of said table, a curling head located above said table at substantially its middle part, a can end stack magazine located at the delivery end of said table, transfer feeding devices operating in said table for moving the can ends first to said curling head and thence to said magazine, means for lifting a said can end from said table and from said feeding device into said curling head, curling instrumentalities operating in said curling head for flange curling a said can end, and means located adjacent said magazine for successively removing the curled can 40 ends from said feeding devices and positioning them in stack formation within said magazine.

9. An apparatus for curling the flanges of can ends and the like, comprising in combination, a horizontal table adapted to support flanged can 45 ends, a curling head located above said table, transfer feeding devices operating in said table for moving the can ends therealong, means for lifting a said can end from said table into said curling head for a flange curling operation, guide bars mounted on said table for holding can ends in their proper path of travel, and means for moving a said guide bar out of guiding position to permit removal of said can ends while on said table.

10. An apparatus for curling the flanges of can ends and the like, comprising in combination, a lift device for supporting a can end to be flange curled, a curling head adapted to be positioned above said lift device, curling instrumentalities comprising a stationary chuck and curling elements carried in said head, means for clamping a said can end between said chuck and said lift device, and actuating means for actuating said curling elements while the said can 60 end is held stationary in said chuck, said curling head having a pivotal mounting so that it may be swung back away from position above said lift device to permit removal of said chuck and curling elements from said can end.

11. An apparatus for curling the flanges of can ends and the like, comprising in combination, a horizontal table adapted to support flanged can ends, a curling head located above said table and hinged thereto, transfer feeding devices op- 75

erating in said table for moving the can ends therealong, means for lifting a said can end from said table into said curling head, curling instrumentalities in said head for performing the curling operation, actuating means mounted on said table for actuating said curling instrumentalities, guide bars mounted on said table for retaining the can ends in their proper path of travel, and means for moving a said guide bar out of guiding position, said curling head being mounted to be movable away from said table without disconnecting its actuating means.

12. An apparatus for curling the flanges of can ends and the like, comprising in combination, a lift device for supporting can ends to be flange curled, a curling head adapted to be positioned above said lift device, curling instrumentalities carried in said head, means for centering a said can end on said lift device relative to said curling instrumentalities, means for raising said lift device to bring its superimposed can end into curling position within said curling head, and actuating means for actuating said instrumentalities to curl the flange of said positioned can end.

13. An apparatus for curling the flanges of can ends and the like, which comprises in combination, a frame, a lift device mounted in said frame and adapted to support a can end to be flange curled, a curling head supported on said frame, curling instrumentalities carried in said head, means for raising said lift device to bring its superimposed end into curling position within said curling head, actuating means including a shaft journaled in said frame for operating said curling instrumentalities to curl said can end flange, and means carried by said head and pivotally mounted on said shaft for permitting hinging of said head relative to said frame while maintaining driving connection with said actuating means.

14. An apparatus for curling the flanges of can ends and the like, which comprises in combination, a frame, a lift device mounted in said frame and adapted to support a can end to be flange curled, a curling head hingedly supported on said frame, curling instrumentalities carried in said head, means for raising said lift device to bring its superimposed end into curling position within said curling head, actuating means for operating said curling instrumentalities to curl said can end flange, and means for holding said head above said lift device and in curling position while the latter is in raised position.

15. An apparatus for curling the flanges of can ends and the like, which comprises in combination, a frame, a curling head hingedly supported on and movable into and out of curling position relative to said frame, a stationary chuck in said head for holding a can end to be flange curled, curling instrumentalities carried in said head and rotatable around said stationary chuck for curling the flanges of a said can end held on said chuck, means for holding said head in curling position on said frame, and means for holding said head while out of curling position and with said stationary chuck and said curling instrumentalities away from said can end.

16. An apparatus for curling the flanges of can ends and the like, which comprises in combination, a frame, a lift device mounted in said frame and adapted to support a can end to be flange curled, a curling head hingedly supported on said frame, curling instrumentalities carried in said head for curling the flanges of can ends held by said lift device, means for holding said head in curling position above said lift device, and means for preventing operation of said curling instrumentalities when said hinged head is out of the curling position.

WILLIAM F. BUTLER.

40
